(57) **CLAIM**

The ornamental design for a docking station with mop cleaning and dust collecting for cleaning robot, as shown and described.

DESCRIPTION

The patent or application file contains at least one drawing executed in color. Copies of this patent or patent application publication with color drawing(s) will be provided by the Office upon request and payment of the necessary fee.

1.1 : Front view of a first embodiment of a docking station with mop cleaning and dust collecting for cleaning robot showing the new design;

1.2 : Rear view thereof;

1.3 : Left view thereof;

1.4 : Right view thereof;

1.5 : Top view thereof;

1.6 : Bottom view thereof;

1.7 : Perspective view thereof;

1.8 : Perspective view thereof;

1.9 : Perspective view thereof;

2.1 : Front view of a second embodiment of a docking station with mop cleaning and dust collecting for cleaning robot showing the new design;

2.2 : Rear view thereof;

2.3 : Left view thereof;

(Continued)

- 2.4** : Right view thereof;
2.5 : Top view thereof;
2.6 : Bottom view thereof;
2.7 : Perspective view thereof;
2.8 : Perspective view thereof; and
2.9 : Perspective view thereof.

The broken lines in the reproductions **1.1** to **1.9** depict portions of the docking station with mop cleaning and dust collecting for cleaning robot that form no part of the claimed design. The yellow portions in the reproductions **2.1** to **2.9** depict portions of the docking station with mop cleaning and dust collecting for cleaning robot that form no part of the claimed design.
